UNITED STATES PATENT OFFICE

FRANK KUSTERLE, OF KENOSHA, WISCONSIN, ASSIGNOR TO SIMMONS COMPANY, OF NEW YORK, N. Y., A CORPORATION OF DELAWARE

HOSPITAL TABLE

Application filed August 12, 1929. Serial No. 385,264.

This invention relates to hospital tables or over-the-bed tables such as are designed for convenient use by those who are required to remain in bed, and particularly for use in hospitals.

The objects of the invention are to provide a hospital table of the type referred to which will be rigid and steady when in use and not readily tipped over; to provide a hospital table which is vertically adjustable to suit the convenience of the person using the table; to provide means for adjustably supporting the table whereby the same may be adjusted upwardly by the person using the same while remaining in bed; to provide an arrangement whereby the table is readily movable to the desired position longitudinally of the bed; to provide a hospital table structure of the class described which can be 20 economically made at a comparatively low cost; and in general, it is the object of my invention to provide an improved hospital table of the class described.

Other objects and advantages of my invention will be understood by reference to the following specification and accompanying drawings in which I have illustrated a hospital table embodying a selected form of my invention, and in which drawings:

30 Fig. 1 is a perspective.

Fig. 2 is a section on the line 2—2 of Fig. 1.

Fig. 3 is a fragmentary section on an enlarged scale taken on a vertical plane extending through one of the pedestals of the table 25 as shown in Fig. 1.

Fig. 4 is a section on the line 4—4 of Fig. 3, and

Figs. 5 and 6 are sections on the lines 5—5 and 6—6 respectively of Fig. 4.

40 Referring now to the drawings, my improved hospital table includes a table top 10 which may be of sheet metal or other suitable material, and which is preferably provided with an upwardly facing ledge or flange 11 which serves to support papers, books or the like when the table top is in upwardly inclined position as shown in Fig.

45 1. The table top 10 is adjustably mounted 50 on a main supporting frame which is adapted

to straddle the width of an ordinary hospital bed.

The table supporting structure according to my present invention includes a pair of pedestals 12 and 13 which are connected at 55 their upper ends by means of a frame element 14. The connecting frame element 14 serves to rigidly maintain the pedestals 12 and 13 in fixed spaced relation and also to maintain the pedestals in upright position, 60 i. e. against tipping in a direction extending crosswise of the bed.

The pedestals 12 and 13 are substantially alike in construction. Therefore, I will proceed to describe in detail the construction of 65 only one of them, and I will describe the pedestal 13 which is shown in Fig. 3, this view being a section looking towards the inside of the pedestal.

By reference to Figs. 1 and 3, it will be 70 seen that the pedestal 13 includes an upright hollow post member 15 which is mounted in a foot member 16, the latter extending transversely of the post and being arranged to extend longitudinally of the bed. The foot 75 member 16 is also preferably a hollow or tubular metal member provided with casters such as 17 at its opposite ends and facilitating movement of the table to or from operative position over a bed. The casters at the

80 opposite ends of the foot are, of course, adapted to rest on the floor, and as shown in Figs. 1 and 3, the hollow post 15 extends upwardly from the foot 16 at a point intermediate the length of the foot member. The post 15 is 85 rigidly secured to the foot member 16 in any suitable manner, preferably by being passed through openings in the top and bottom walls of the foot member as clearly shown in Fig.

90 3, a collar 18 and lower end cap 19 being provided as shown. The parts may be welded or otherwise secured in assembled position so as to form a rigid and durable structure. It will be seen that the post 15 is maintained in upright position, that is to say, against 95 falling or tipping in the direction of the length of a bed by reason of its intermediate position on the elongated foot 16.

The pedestals 12 and 13 are preferably connected at their upper ends as above described 100

by means which is vertically adjustable so that the height of the table top, which is carried by the connecting means, may be adjusted to suit the individual requirements, 6 and also so that the connecting element is capable of being elevated sufficiently to pass over the end frame of the bed without lifting the pedestals from the floor. This end is accomplished by securing the frame part 14 to an element which is vertically slidably mounted on the upright posts of the pedestals. In the present instance, this mounting includes a tubular metal member 20 which telescopes over the post 15 in a snug sliding fit 10 thereafter. For locking the telescoping members 15 and 20 in the desired position of vertical adjustment, I provide a spring-pressed dog 21 which is pivotally mounted as indicated at 22 in a U-shaped bracket member 23. The bracket 23 is anchored in place adjacent the upper end of the post 13 in any suitable manner, for instance, by riveting or welding. The dog 21 includes a tooth portion 24 which projects outwardly through an opening 25 20 in the inner wall part of the post 15, and is adapted to fit into openings such as 26 in the adjacent wall part of the tubular member 20. As shown, there is a series of vertically spaced openings 26 in the inside wall of the tubular member 20 so that the said member is adapted to be locked by the pawl 21 in any one of a plurality of vertically adjusted positions. The dog 21 is preferably in the shape of a bell crank, one arm of which carries the tooth 24 and the other arm of which is pivotally connected to a control rod 27. A spring 28 fitting around the control rod 27 and compressed between the bottom part of the bracket 23 and a washer 29 at the upper 30 end of the control rod, serves to yieldingly urge the dog to turn in such a direction that the tooth 24 thereof is caused to enter the respective openings 26. The control rod 27 extends downwardly from the locking dog, 40 inside of the post 13 and projects through an opening in the cap 19 as clearly shown in Fig. 3, and the lower end of the control rod is connected to a pivotally mounted treadle member 30. The treadle member 30 is pivoted at one end as shown at 31 to the under side of the foot member 16, and at its free end is provided with a treadle rod 32 which is secured to the member 30, passes upwardly through the foot member 16 through suitable 50 openings provided therein, and which is provided with a head or button member 33 adapted to be depressed by stepping thereon or otherwise. It will be seen that when the button 33 is stepped on, the control rod 27 will be depressed against the pressure of the spring 28 and the tooth 24 withdrawn from engagement with one of the openings 26.

The arrangement of the openings 26 and the pawl or dog 21 is preferably such that the 60 table may be adjusted upwardly merely by

lifting the same, and without requiring depression of the pedal 33. This is accomplished by providing the lower side of the tooth 24 with an inclined face as indicated at 34 so that upward movement of the tubular member 20 will be effective to cam the dog inwardly while downward movement of the tubular member, under its own weight, is effectively prevented by engagement of the lower side of the tooth with the edge 35 of the tubular post 15 adjacent the bottom of the opening 25 therein, through which the tooth projects. Pivotal movement of the dog 21 under the weight of the table top, and also under the influence of the spring 28 is further limited by reason of the control rod 27 which, at its lower end, is provided with a cotter pin 36, or other suitable key element which engages the bottom of the treadle 30 so as to pull the same upwardly into engagement with the bottom of the cap 19.

The inside face of each of the pedestals is provided with a cushion strip or bumper 37 which is adapted to prevent contact of the metal post members with the bedstead, and thereby to prevent scratching or other marring or damage to the bedstead as an incident to movement of the table into or out of position over the bed, or as an incident to movement of the table while in use over the bed. The bumper strip 37 may be anchored to the inside of the respective pedestals in any suitable manner, but I prefer to anchor it by means of a metal channel strip 38 which is provided with inwardly facing flange portions 39-39 adapted to interlock with the cushion strip substantially as shown in Fig. 5.

The metal strip 38 is welded or otherwise secured to a metal face strip 40 which fits over the inside face of the tubular member 20 and is secured thereto by soldering, welding or in any other suitable manner so that the bumper strip is effectively anchored to the pedestal. The face strip 40 is preferably provided with an outwardly offset center portion as shown in Fig. 5 so that it will not prevent the tooth 24 of the locking dog from projecting through the respective openings the required distance. The facing strip 40 obviously serves to conceal the openings 26 whereby appearance of the structure is improved. The facing strip 40 also facilitates cleanliness in that it excludes dirt and other foreign matter from the openings in the side walls of the post members, and also from the inside thereof.

The upper ends of the tubular members 20 are preferably bent inwardly as shown in Fig. 1, and the frame structure 14 is secured to the inner ends of the said bent end portions. The frame structure 14 may conveniently consist of tubular metal members provided with bent ends substantially as shown, the bent ends being secured to the pedestal members so as to form a frame including

120

125

130

spaced front and rear bars 41 and 42, these parts being rigidly maintained in position by being welded to the respective pedestal parts.

5 The table top 10 may conveniently be hinged to the front bar 41 by means of hinges as indicated at 43, which hinges preferably include a leaf 44 extending across the entire width or height of the table top so as to reinforce the same, the other leaf 45 of each hinge being secured to the frame part 41 in any suitable manner.

For adjustably supporting the table top in a desired position of pivotal adjustment, I 15 provide a bail member 46 which is pivotally secured to the back of the table member 10 as shown in Figs. 1 and 2, the bottom part of which bail is adapted to fit in notches 47 provided in rack bars 48—48, the latter extending between and being secured to the front and rear bars 41 and 42 of the frame 14. As clearly shown in Fig. 2, certain of the notches or recesses 47 adjacent the front end of the rack bars 48 are disposed at a rearwardly facing angle so as to facilitate insertion of the bail therein when the table part is to be disposed in a position closely approximating a vertical position. When the table top is disposed in substantially horizontal 25 position as shown in broken lines in Fig. 2, the bail 46 fits in the rearmost notches of the rack bars 48.

In the present instance, I have shown the telescoping tubular members 15 and 20 as 35 being rectangular in form. It will accordingly be seen that the foot members 16 are maintained against rotation about the axis of the telescoping members so that both of the foot members will remain substantially 40 parallel to each other at all times. Of course, other means may be provided for slidably connecting the respective pedestal parts while at the same time preventing relative rotation therebetween so that the bed 45 straddling frame structure will be readily movable longitudinally of the bed.

Tipping of the foot members in a direction extending crosswise of the bed is obviously prevented by reason of the relatively fixed 50 telescoping members 20 which preferably fit over substantially the entire length of the upright posts when the table is in its lowermost position as shown in Fig. 1. Wear plates such as indicated at 49—49 may be 55 provided on the foot members 16 for preventing wearing of the foot members proper by reason of a person stepping on the foot member, in the event that this becomes necessary, to hold the pedestals down when it is desired to 60 raise the table top.

The above described structure may readily be made comparatively light in weight so as to be easily moved relative to a bed and so as to be readily upwardly adjustable, even by a 65 person confined to the bed. Also, the struc-

ture is such that parts are rigidly maintained in their described positions and the table top thus rigidly supported.

I am aware that changes may be made in the above described hospital table construction without departing from the spirit of my invention, the scope of which should be determined by reference to the following claims, construing the same as broadly as possible consistent with the state of the art. 75

I claim as my invention:

1. In a hospital table, the combination of a table top, and a main supporting frame adapted to straddle the width of the bed for supporting said table top over the bed, said 80 supporting means including a pair of pedestals respectively disposed on opposite sides of the bed, spaced members respectively disposed forwardly and rearwardly of said pedestals and rigidly connected to the upper 85 ends thereof, a rack bar rigidly connected to and extending between said spaced connecting means, said table top being pivotally mounted on said front connecting means and provided with means pivotally connected 90 thereto for adjustably engaging the teeth of said rack bar to maintain the table top in the desired position of adjustment.

2. In a hospital table, the combination of a table top, a main support for said table 95 top including a foot member, a hollow pedestal extending upwardly from said foot member, a member slidably mounted on said hollow post member for vertically adjustably supporting said table top, means mounted on the inside of said hollow pedestal for locking 100 said member in the desired position of vertical adjustment, and foot controlled means mounted in said pedestal foot for releasing said locking means. 105

3. In a device of the class described, an outer tubular post having a plurality of perforations in a longitudinal row, an inner tubular post telescoping said outer post and having means therein engageable in said 110 perforations for adjusting the elevation of said outer post relative to the inner post, a resilient bumper extending longitudinally of said outer post, and a mounting for said bumper secured to said outer post so as to conceal said perforations and providing 115 space for said adjusting means when the latter is extending through said perforations.

4. In a device of the class described, an outer tubular post having a plurality of perforations in a longitudinal row, an inner tubular post telescoping said outer post and having means therein engageable in said 120 perforations for adjusting the elevation of said outer post relative to the inner post, a resilient bumper extending longitudinally of said outer post, and a mounting for said bumper secured to said outer post so as to conceal said perforations and providing 125 space for said adjusting means when the lat- 130

- ter is extending through said perforations, said mounting comprising an approximately U-shaped member in cross section embracing said outer post, the web of said U bulging away from said post, and a C-shaped member secured to said web.
5. In a device of the class described, a pair of vertical posts, elongated foot members secured to said posts intermediate the ends of said foot members, a second pair of posts slidably but non-rotatably telescoping said first post, means for securing said second posts in vertically adjusted position relative to said first posts, a pair of spaced substantially parallel bars connected to said second posts at a point intermediate said bars so as to be vertically movable therewith, a table hinged to one of said bars, and means for adjusting the angle of said table relative to the plane of said bars.
- 10 6. In a device of the class described, a pair of vertical posts, elongated foot members secured to said posts intermediate the ends of said foot members, a second pair of posts slidably but non-rotatably telescoping said first post, means for securing said second posts in vertically adjusted position relative to said first posts, a pair of spaced substantially parallel bars connected to said second posts at a point intermediate said bars so as to be vertically movable therewith, a table hinged to one of said bars, and means for adjusting the angle of said table relative to the plane of said bars, said table-adjusting
- 15 30 35
- 20 25 30 35
- means comprising a rack extending between said parallel bars, and means pivoted to said table and engageable with said rack.

FRANK KUSTERLE.
